VACUUM TUBE AND MOUNTING THEREFOR

William Thomas Gibson, London, England, assignor to Standard Telephones and Cables Limited, London, England, a British company

Application January 5, 1946, Serial No. 639,286
In Great Britain January 16, 1945

6 Claims. (Cl. 250—27.5)

1

The present invention relates to electron discharge devices including vacuum tubes, and mountings therefor.

It is well known that considerable troubles in electrical circuits utilising electron discharge devices arise from poor contacts between the pins or conductors which serve as terminals for the electrodes of the device, and the corresponding sockets or contact members of the holder. In order to eliminate these poor contacts it is desirable to solder the electrode terminal conductors directly into the associated circuit. While several proposals to attain this end have been made hitherto, the practice of soldering the vacuum tube directly into the circuit has never been adopted because such proposals have not been found practicable.

It is the object of this invention to provide a really practical method of connecting an electron discharge device into circuit utilising only permanent connections, that is, without the use of contact devices.

The object is achieved according to the invention by providing an electron discharge device substantially completely enclosed in a conducting screen, and having soldering tags secured to the lead-out conductors for the electrodes of the device.

The invention also provides an electrical circuit arrangement comprising circuit elements including an electron discharge device having electrodes enclosed in a metallic screen and rigid lead-out conductors for the electrodes passing outside the screen, and wires connecting the device to other circuit elements soldered to the said lead-out conductors.

It is possible to adapt standard types of vacuum tubes according to the invention, either unaltered, or alternatively without the usual basing arrangements.

The invention will be described with reference to the accompanying drawings in which—

Fig. 1 shows a sectional view of an electron discharge device according to the invention;

Fig. 2 shows a top view of the device;

Fig. 3 shows an exploded view of the details of the device;

Fig. 4 shows a transverse section through the cylindrical screen of the device;

Fig. 5 shows a perspective view of another device according to the invention; and

Figs. 6 and 7 show perspective views of a soldering tag for the device of Fig. 5.

In the embodiment of the invention shown in Figs. 1 to 4, a vacuum tube 1 is enclosed in a close

2

fitting metal shield or can 2. The bottom of the can is closed by a metal plate 3 carrying a metal boss 4 which is designed to give mechanical protection to the seal-off tip 5 of the vacuum tube envelope. The plate 3 has holes 6 adapted to clear the pin or rod terminals 7 for the electrodes of the vacuum tube. Over the plate 3 is placed a ring or disc 8 of insulating material such as phenol fibre. On top of this are placed connecting and soldering tags 9 formed from bent metal strip. These tags are held in position by a star-shaped piece 10 of insulating material such as phenol fibre, and are intended to be soldered to the wires leading to the other elements of the circuit with which the tube is used. This assembly is locked into position, for example, by spinning over the end of the shielding can, as indicated in Fig. 1. The inner ends of the soldering tags are securely connected, by welding or soldering (for example) to the pin terminals 7. Means are provided for securing the can 2 into a chassis, which may be of metal. For example, close to the open end of the can several bosses 11 are pressed outwards round the circumference of the can. The design should be such that the bosses are springy. The can 2 may then be inserted into a metal chassis plate 12 which has a hole punched out to receive the can. This hole should be very slightly smaller in diameter than the circumscribing circle of the outsides of the bosses. The can may, therefore, be snapped through the hole in the plate 12 where it will be held in position, but can be extracted by a steady pull when required. As shown in Fig. 1, the can 2 is formed so that it is locked into the chassis between the bosses 11 resting on one side of the plate 12 and the projecting rim 13 provided round the circumference of the can 2 which rests against the other side of the plate 12.

40 The can may also be provided with an additional elongated ridge or boss 14 (Fig. 3) arranged parallel to the axis of the vacuum tube, which can engage in an appropriate slot (not shown) in the hole in the plate 12, which will thus orientate the tube, thereby ensuring that the soldering tags 9 always come into the same position in relation to other equipment. This will facilitate the wiring of the tags 9 to the other equipment.

50 The boss 4 may be provided with an extension (not shown) which may be used as a finger grip to assist in inserting the vacuum tube into, and withdrawing it from, the chassis plate 12.

This embodiment of the invention has the following advantages:

1. No vacuum tube holder is necessary.
2. The soldering or connecting points are accurately located in the chassis in which the tube is assembled.
3. The tube is electrostatically screened.
4. The tube is locked in position.
5. No basing cement is necessary, and loose bases are an impossibility.
6. Either a pressed glass valve base or a pinch stem may be used.

The arrangement which has just been described is also applicable without essential change to the type of vacuum tube in which the lead-out conductors for the electrodes are relatively flexible wires or the like. A somewhat simpler arrangement is, however, practicable only for the type in which these lead-out conductors are rigid pins or rods sealed through the envelope of the tube. This embodiment is shown in Figs. 5, 6 and 7. The can 2 is in this case closed by the plate 3 carrying the boss 4 as in Figs. 1 to 4. The tags 9 and insulating discs 8 and 10 are however omitted, the can 2 being simply spun over the plate 3.

To each of the pin terminals of the tube is attached a tag 15 shown enlarged in Fig. 7. This tag is made from a flat L-shaped metal detail of the shape shown in Fig. 6, the end portion 16 being rolled over in the manner shown in Fig. 7 to form a socket which is slipped over the projecting end of the pin terminal of the vacuum tube, and is then securely welded or soldered thereto. A hole 17 at the other end of the tag may be used for anchoring the wire to which the tag is subsequently soldered when the tube is to be connected in the associated circuit. The can 2 may be provided with bosses (not shown) similar to 11 and 14 shown in Figs. 1, 3 and 4.

This arrangement has the further advantage that the additional capacity introduced by the terminal tags is less than in the case of Figs. 1 to 4, and this will be an important consideration at high frequencies.

An alternative way of carrying out the invention is applicable in the case of the well known type of tube already provided with a practically totally enclosing metal screen, and having pin terminals projecting beyond the closing metal base plate. A holder of the kind usually used with such a tube is obtained, and the tube is inserted therein in the usual manner. Each of the pins is then soldered or welded into the corresponding socket of the holder, and the complete assembly so formed is treated as a unit and is then fixed in the chassis in any convenient way, for example by using the normal fixing means for the holder. The wires leading from the other circuit elements are then soldered to the holder tags in the usual way.

The case where the pin terminals of the vac-

uum tube make contact with flat springs in the holder may be treated in a similar way, the pins being soldered or welded to the flat springs.

What is claimed is:

5. An electron discharge device comprising an envelope of insulating material having conductors for the electrodes of the device sealed through said envelope, a metal envelope enclosing said insulating envelope, a base plate provided with apertures and mounted on said metal envelope with said conductors passing through said apertures, and metallic tags secured to said conductors adjacent said apertures whereby said discharge device is effectively screened.
10. An electron discharge device according to claim 1 in which said tags are shaped to bend from the point at which they are secured to said conductors towards said apertures and which further comprises insulating plates securing said tags adjacent said apertures.
15. An electron discharge device according to claim 1 further comprising bosses raised on the outside surface of the said metal envelope for removably locking the device into a corresponding aperture in a holder.
20. An electron discharge device comprising an envelope of insulating material having a vacuum tight seal-off tip and conductors for the electrodes of the device sealed through said envelope, a metal envelope enclosing said insulating envelope, a base plate provided with apertures and a boss and mounted on said metal envelope with said conductors passing through said apertures and said boss fitting around said seal-off tip, and metallic tags secured to said conductors adjacent said apertures, whereby said discharge device is effectively screened.
25. An electron discharge device according to claim 1, further comprising means for insulatedly securing said tags to said base plate.
30. An electron discharge device according to claim 1 in which one end of each said tag is secured to its respective conductor and the other end comprises means for rigidly connecting the tube to an external circuit and which further comprises means for insulatedly securing parts of the tags intermediate the ends thereof to the base plate.
35. An electron discharge device according to claim 1 in which one end of each said tag is secured to its respective conductor and the other end comprises means for insulatedly securing parts of the tags intermediate the ends thereof to the base plate.
